(57) **CLAIM**

The ornamental design for a bypass projection and nozzles for a water filter cartridge, as shown and described.

DESCRIPTION

FIG. 1 is a bottom perspective view of a bypass projection and nozzles for a water filter cartridge of this invention;

FIG. 2 is a front view of the bypass projection and nozzles of FIG. 1;

FIG. 3 is a back view of the bypass projection and nozzles of FIG. 2;

FIG. 4 is a right side view of the bypass projection and nozzles of FIG. 2, with the opposing side being a mirror image thereof;

FIG. 5 is a top perspective view of the bypass projection and nozzles of FIG. 1;

FIG. 6 is a top view of the bypass projection and nozzles of FIG. 4;

FIG. 7 is a bottom perspective view of an embodiment of the bypass projection and nozzles for a water filter cartridge of FIG. 1;

FIG. 8 is a front view of the bypass projection and nozzles of FIG. 7;

FIG. 9 is a back view of the bypass projection and nozzles of FIG. 8;

FIG. 10 is a right side view of the bypass projection and nozzles of FIG. 8, with the opposing side being a mirror image thereof;

FIG. 11 is a top perspective view of the bypass projection and nozzles of FIG. 7; and,

FIG. 12 is a top view of the bypass projection and nozzles of FIG. 10.

The broken line showing of portions of a water filter cartridge are for the purpose of illustrating environmental structure and form no part of the claimed design.
